DESIGN FOR A SUIT

Jules Freedman, New York, N. Y.

Application May 21, 1947, Serial No. 139,177

Term of patent 3½ years

(Cl. D3—4)

To all whom it may concern:

Be it known that I, Jules Freedman, a citizen of the United States of America, residing in New York city, county of Kings, and State of New York, have invented a new, original and ornamental Design for a Suit, of which the following is a specification, reference being had to the accompanying drawing, forming part thereof, wherein,

Figure 1 is a front elevational view of a suit showing my new design.

Figure 2 is a rear elevational view of the suit shown in Figure 1.

I claim:

The ornamental design for a suit, substantially as shown.

JULES FREEDMAN.
